CHESTER PENFIELD, OF NEW BRITAIN, CONNECTICUT.

Letters Patent No. 85,760, dated January 12, 1869.

IMPROVEMENT IN ALARM-BELLS.

The Schedule referred to in these Letters Patent and making part of the same.

To all whom it may concern:

Be it known that I, CHESTER PENFIELD, of New Britain, county of Hartford, and State of Connecticut, have invented certain new and useful Improvements in Alarm-Bell; and to enable others skilled in the art to make and use the same, I will proceed to describe its construction and operation by referring to the drawings, in which the same letters indicate like parts in each of the figures.

The nature of this invention will be understood from the specification and drawings.

Figure 1 is a face view of a door and frame, to which this invention is attached.

Figure 2 is a side view of the actuating-device, secured to the frame-work of the door.

a is the plate, to which the bell is secured.

b is the hammer, secured by its handle-hub, *c*, to the stud-pin *d*.

e is an actuating-arm, attached to the same hub, *c*, of the hammer-handle.

f is a spring, coiled around the pin *g*, one arm of which has its bearing against the bell-spindle, while the opposite end takes bearing against the hammer-handle, and holds it (the hammer) at rest until acted upon by the actuating-device (see fig. 2) which is secured to the frame-work of the door.

The hammer-handle may be extended through the hammer, so that the actuating-device may act directly upon the outer end thereof, and thus dispense with the independent actuating-arm *e*.

While at rest, this hammer-handle or arm *e* takes bearing against the detent *h*, to prevent the hammer from resting against the rim of the bell.

i is a wall-plate of the actuating-device, by which it (the device) is secured to the casing.

k is a stud-post, projecting forward at right angle from the plate *i*, having a slit or opening in its outer end, in which the triangular-shaped vibrating catch *m* is secured by a pin passing through the stud *k*, and one corner or angle of said plate *m*.

This angular plate *m* is allowed to vibrate back and forth in the slit, so that first one edge, then the other, is (by its vibration) brought into position parallel with the sides of stud-pin *k*, so that it will fall by its own gravity into position to actuate the bell-hammer, and be lifted, and again fall to its position, when the door is closed, in readiness for a new operation.

This plate is held in an elevated, inoperative position, when desirable, by means of a latch, *n*, which enters an orifice, *o*, formed in the side of the plate *m*. Thus the door may be opened and closed without actuating the bell; and, when desirable to leave it in position for operation, it is only necessary to turn the latch back out of the orifice *o*.

I believe I have thus shown the nature, construction, and advantage of this invention, so as to enable others skilled to make and use the same therefrom.

What I claim, therefore, and desire to secure by Letters Patent, is—

The arrangement of the triangular vibrating catch-plate *m*, stud and jamb-plate *k* *i*, in combination with the actuating-arm *e* of the bell, substantially as described.

CHESTER PENFIELD. [L. S.]
